**7-CHLORO-6-DEMETHYL-TETRACYCLINE
FERMENTATION**

This application is a continuation-in-part of my copending application Ser. No. 508,331, filed Nov. 17, 1965, now abandoned.

This invention relates to an improved process for the production of 7-chloro-6-demethyltetracycline and, more particularly, is concerned with the selective production of 7-chloro-6-demethyltetracycline by fermentative biosynthesis using strains of *Streptomyces aureofaciens* which impart a color to their whole harvest mashes such that a positive value of δR is obtained when the values of the percent reflectance of a 1:200 aqueous dilution of the whole harvest mash at 460 $\mu\mu$, 540 $\mu\mu$, 560 $\mu\mu$ and 660 $\mu\mu$ are inserted in the following formula:

$$\delta R = R_{540} + R_{560} - 1.1R_{460} - 0.9R_{660} - 2.0$$

The novel mutant strains of the present invention are strains of the species *Streptomyces aureofaciens*. The representative *S. aureofaciens* strains described below are direct descendants of the 7-chlorotetracycline-producing *S. aureofaciens* A-377 soil isolate described in U.S. Pat. No. 2,482,055 to Duggar and deposited at the Northern Regional Research Laboratories, Peoria, Ill. and indexed as NRRL 2209, derived by mutagenic processes known to the art, e.g., ultraviolet irradiation, nicotine, and nitrogen mustard. Typical mutant strains of *S. aureofaciens* which possess the unique properties described herein have been designated by me as 1E-1352, 1E-1354, 1E-1355 and 1E-2803. Viable representative cultures of the novel mutant strains of the present invention have been deposited at the Northern Regional Research Laboratories, Peoria, Ill. and have been assigned the following accession numbers:

Strain	NRRL No.
1E-1352	3201
1E-1354	3202
1E-1355	3203
1E-2803	3235

It will be understood, of course, that mutants which possess this unique property of imparting a specific color to their whole harvest mashes may be derived from these strains by conventional procedures. These mutants may vary somewhat in general morphological and physiological characteristics as do the various strains of the *S. aureofaciens* species. It is also to be expected that 7-chloro-6-demethyltetracycline-producing strains of *S. aureofaciens* of the invention, i.e., with the required positive δR value, may be found in nature or derived from presently isolated strains of *S. aureofaciens* by mutagenic methods well known to the art. The strains of the present invention display the fundamental characteristics of the species *S. aureofaciens* and may be readily identified as members of this species although differing from previously described strains of *S. aureofaciens*, not only in pigmentation on solid media, but also in the colors of the whole harvest mashes obtained therewith.

The antibiotic 7-chloro-6-demethyltetracycline was first described and claimed, together with methods of its production, in the McCormick et al. U.S. Pat. No. 2,878,289 wherein a 7-chloro-6-demethyltetracycline-producing strain of *S. aureofaciens* was cultivated in a fermentation medium. That patent also discloses that other tetracyclines, such as 6-demethyltetracycline, 7-chlorotetracycline and tetracycline are produced at the same time in a fermentation medium when the fermentation conditions, including the micro-organism therein disclosed, are used. Additionally, that patent discloses that 7-bromo-6-demethyltetracycline is a concomitant product when bromine is a constituent of the fermentation medium. Further evidence of the production of more than one tetracycline in a fermentation medium in which demethylchlorotetracycline is produced may be found in the Perlman et al. U.S. Pat. No. 3,028,311 and the Neidleman U.S. Pat. No. 3,061,552 wherein so-called 6-methylation in-

hibitors are present in a fermentation medium in which a 7-chlortetracycline-producing strain of *S. aureofaciens* is used.

Additional disclosures of the production of 7-chloro-6-demethyltetracycline by cultivating 7-chlortetracycline producing strains of *S. aureofaciens* in the presence of 6-methylation inhibitors are shown in the Goodman et al. U.S. Pat. Nos. 3,019,172 and 3,127,328. These processes are also faced with the problem of concomitant formation of other tetracyclines. Thus, in each a mixture of 7-chlortetracycline, tetracycline, 7-chloro-6-demethyltetracycline and 6-demethyltetracycline is produced.

The concomitant production of 6-demethyltetracycline (or other tetracyclines) is objectionable when 7-chloro-6-demethyltetracycline is the principal product being sought. While the specifications of pharmaceutical quality 7-chloro-6-demethyltetracycline permit small quantities of 6-demethyltetracycline to be present, the presence of any sizable quantity of 6-demethyltetracycline is objectionable. The presence of these two antibiotics in the same fermentation mash in any sizable amounts also involves difficult problems of separation in the refining or extraction procedures when 7-chloro-6-demethyltetracycline is the desired product. It is possible, of course, to extract the two antibiotics from the fermentation mash and by selective refining procedures to effect a separation of the antibiotics. However, the refining procedures for effecting separation of the antibiotics are difficult and usually involve some loss in total antibiotic potency. Moreover, in those instances where 7-chloro-6-demethyltetracycline is the principal product of the fermentation, 6-demethyltetracycline is unwanted and is customarily removed and discarded. Hence, any method that results in the increased production of 7-chloro-6-demethyltetracycline and the lessened concomitant production of 6-demethyltetracycline constitutes a marked contribution to the art of antibiotic fermentation.

It is indeed surprising that the novel mutant strains of *Streptomyces aureofaciens* of the present invention will produce, in a conventional fermentation, 7-chloro-6-demethyltetracycline with no more than 5 percent of 6-demethyltetracycline as a concomitant product. Furthermore, there is no detectable production of tetracycline or 7-chlorotetracycline. The discovery of these strains obviates the need for costly and difficult extraction and purification procedures, since the crystals of 7-chloro-6-demethyltetracycline obtained are of pharmaceutical quality. Obviously the discovery of these strains denotes a marked contribution to the art of producing the highly effective antibiotic 7-chloro-6-demethyltetracycline.

In general, these new strains and the strains which are presently known in the art which produce 7-chloro-6-demethyltetracycline in conventional media may be divided into three categories: (1) *S. aureofaciens* strains ATCC 12551, 12552, 12553 and 12554 which are described in U.S. Pat. No. 2,878,289 McCormick et al. and which produce varying amounts of 7-chloro-6-demethyltetracycline, 6-demethyltetracycline, tetracycline and 7-chlorotetracycline, (2) *S. aureofaciens* strains V-138, E-475, E-1311, ED-1723, ED-2047 and ED-2314 which are disclosed in the following patents: V-138 in U.S. Pat. No. 3,037,916 (Goodman), E-475, E-1311, ED-1723 and ED-2047 in U.S. Pat. No. 3,050,446 (Goodman), ED-2314 in U.S. Pat. No. 3,145,154 (Goodman); and which produce varying amounts of 7-chloro-6-demethyltetracycline and 6-demethyltetracycline to the virtual exclusion of methylated tetracyclines; and (3) the new strains of the present invention, e.g., 1E-1352, 1E-1354, 1E-1355 and 1E-2803, which produce 7-chloro-6-demethyltetracycline to the virtual exclusion of all other tetracyclines.

The novel mutant strains of the present invention may be distinguished from the two groups of prior art strains by a mathematical interpretation of the spectrophotometric reflectance curves of their respective whole harvest mashes. More precisely, when the percent reflectance of diluted samples (1:200 aqueous) of the whole harvest mashes of good yield (such as the examples set forth hereinafter) of the novel

strains of the present invention is measured at specific wavelengths (460 m μ , 540 m μ , 560 m μ and 660 m μ) and the percentage reflectances in these specific wavelengths are inserted in the formula:

$$\delta R = R_{540} + R_{560} - 1.1R_{460} - 0.9R_{660} - 2.0$$

a definite pattern appears. Each of the representative strains of the present invention, 1E-1352, 1E-1354, 1E-1355 and 1E-2803, produce a positive δR value (greater than 0) while each of the representative strains of the prior art produce a negative δR value (less than 0). The letter R denotes the percent reflectance value at some particular wavelength, for example, R_{560} is the percent reflectance value at a wavelength of 560 m μ .

FIGS. 1 through 14 of the drawings are spectrophotometric reflectance curves obtained when 1-centimeter glass cells are filled with a diluted (1:200) whole harvest mash sample which is taken from the harvest fermentation broth of the novel mutant strains of the present invention as well as the additional 10 previously described prior art strains listed in table I. The spectrophotometric reflectance curve of a material constitutes a permanent record that does not require maintenance of a sample. Furthermore, the units in which the curve is expressed are internationally understood and accepted as a means of measuring color. In FIGS. 1 through 14, the wavelength of light in millimicrons is plotted as the abscissa against the reflectance as the ordinate. The wavelength of light has been adopted internationally as the fundamental standard of length to which all other standards of length are referred. These spectrophotometric reflectance curves were determined with a 30 recording spectrophotometer known as the General Electric Hardy Recording Spectrophotometer with the sample backed with magnesium oxide, the reference standard being magnesium oxide, and with the specular component excluded. The curves are recorded on General Electric Co. Chart paper NP 35 62581.

With regard to the aforementioned spectrophotometric determination it should be noted that dilution of the whole harvest mash is necessary to produce the mathematical results as stated. If the whole harvest mash is used undiluted, the difference in the δR value between the new and prior art strains will not be evident. It is only when the whole harvest mash is diluted with water at the rate of one part of whole harvest mash to 199 parts of water that the unusual results of a positive δR value for the new strains and a negative δR value for the prior art strains becomes evident.

A "whole harvest mash" is the untreated mash obtained after a fermentation employing the following medium:

Starch—45 grams
CaCO₃—10.5 grams
NH₄Cl—1.5 grams
Cottonseed flour—45 grams
Yeast—1.5 grams
Water—q.s. to—1000 ml.
Lard oil—3% (Vol./vol. of medium)

has proceeded to the point where biosynthesis of the primary antibiotic product has stopped for all practical purposes. Generally, under the conditions as set forth hereinbelow, the antibiotic potency of the fermentation mash, as may be conventionally determined, ceases to rise appreciably after the fermentation has proceeded for from about 140 to about 160 hours.

The novel mutant strains of *S. aureofaciens* of the present invention which produce virtually no other tetracycline except 7-chloro-6-demethyltetracycline possess essentially the same morphological characteristics as do the strains which concomitantly produce 7-chlorotetracycline, tetracycline, 7-chloro-6-demethyltetracycline and 6-demethyltetracycline and those strains which produce 7-chloro-6-demethyltetracycline and a substantial proportion of 6demethyltetracycline, but differ among themselves in the same general manner that these prior art strains differ from each other as has been described in a number of scientific papers which have been published. The data appearing below will serve to further

distinguish the novel mutant strains of *S. aureofaciens* from the original A-377 strain available as NRRL 2209 and the McCormick et al. strain, ATCC No. 12551 (S-604). In the following color observations on a variety of media, the color data of strain S-604 (ATCC 12551) have been reproduced from U.S. Pat. No. 2,878,289.

To illustrate the visual color variations among the novel mutant strains of *S. aureofaciens* of the present invention, these strains were grown on AP4 agar and the following observations were made.

Color observations 1: *S. aureofaciens*: AP4 Agar: Six-day incubation at 26.5° C.

Single colonies			
Strain	Major colony type I	Minor colony type II	Mass growth
1E-1352	Chocolate brown to deep brown mahogany.	Ebony brown	Chocolate brown to dark brown mahogany.
20 1E-1354	Oak brown to deep brown.	Dark brown mahogany.	Copper brown to chocolate.
1E-1355	Deep brown to chocolate brown.	do	Dark brown mahogany.
1E-2803	do	do	Cocoa brown.

(5) OTHER AGAR MEDIA

	Strain 1E-1352	Strain 1E-1354
15	Medium	Strain 1E-1352
	Nutrient agar.	Poor to fair growth; dark spice brown to chocolate brown. No aerial hyphae. Light amber soluble pigment. Reverse: Chocolate brown.
20	Glucose asparagine-meat extract agar.	Abundant growth; copper brown. Abundant aerial hyphae; pussywillow grey becoming ashes. Sporulation: abundant. Deep amber soluble pigment. Reverse: Deep brown to dark brown mahogany.
25	Purple milk.	Pronounced growth collar; taupe brown to rose brown. Little significant pH change. False alkaline color reaction due to pigment diffusion. pH 6.55 at 2 weeks.
30	Potato slants.	Abundant growth; maple to light brown. Abundant aerial hyphae. Moderate to abundant sporulation. Deep yellow soluble pigment. Reverse: Maple to light brown.
35	Medium	Strain 1E-1355
	Purple milk.	Pronounced growth collar; taupe brown to rose brown. Little significant pH change. False alkaline color reaction due to pigment diffusion. pH 6.8 at 2 weeks.
	Potato slants.	Profuse, moist crenulated growth; chestnut brown to chocolate brown becoming ebony. Rose taupe soluble pigment. No aerial hyphae.
40	Medium	Strain 1E-1355
	Nutrient agar.	Thin growth; Dark spice brown to chocolate brown. No aerial hyphae. Very light amber soluble pigment. Reverse: chocolate brown.
45	Glucose asparagine-meat extract agar.	Abundant growth; cocoa brown to copper brown. Abundant aerial hyphae; ashes. Abundant sporulation. Deep yellow soluble pigment. Reverse: cocoa brown to copper brown.
50	Purple milk.	Pronounced growth collar; taupe brown to rose brown. Little significant pH change. False alkaline color reaction due to pigment diffusion. pH at 2 weeks.
55	Potato slants.	Abundant growth. Heavy aerial hyphae mottled. Rose taupe to fawn to camel. Sporulation: abundant. Reverse: taupe brown. Reddish brown soluble pigment.
60	Medium	Strain A-377
	Nutrient agar.	Poor growth. Taupe brown to dark brown. No aerial hyphae. Reverse: Taupe brown. Reddish brown soluble pigment.
65	Glucose asparagine-meat extract agar.	Slight deep red mahogany growth collar. Little significant pH change nor apparent peptonization. Slight false alkaline color reaction due to diffusion of soluble pigment.
70	Purple milk.	Profuse, moist smooth nodulated growth; dark brown mahogany with peach tan trace. Aerial hyphae; none to abundant becoming white to camel. Sporulation abundant in areas of heavy aerial hyphae. Chocolate to chocolate brown soluble pigment.
75	Medium	Strain 1E-2803
	Nutrient agar.	Poor to fair confluent growth; clove brown to sepia brown. No aerial hyphae. Tawny diffusible pigment tinted reddish brown. Reverse: Clove brown to sepia brown.
	Glucose asparagine-meat extract agar.	Abundant growth; deep brown. Abundant, compact aerial hyphae, ashes. Abundant sporulation. Light to moderate reddish brown diffusible pigment becoming amber. Reverse: Deep brown becoming dark brown mahogany.
	Purple milk.	Slight white to pale yellow growth collar. Little significant pH change nor apparent peptonization in 15 days.

Potato plants. Profuse, moist smooth nodulated growth; light melon yellow to antique rose. Aerial hyphae trace. No soluble pigment.

Profuse, moist, crenulated growth; brown mahogany becoming ebony to chocolate brown. Occasional areas of dense white aerial hyphae at separated foci. Diffusible pigment: rose taupe to taupe brown.

(6) MICROSCOPIC OBSERVATIONS

<i>S. aureofaciens</i>	Glucose asparagine beef extract agar	Q4 agar
Strain 1E-1352:		
Mycelium.....	Flexuous, continuous, branched. Diameter 0.8 to 1.2 μ .	Flexuous, continuous, branched. Diameter 0.8 to 1.2 μ .
Spores.....	Spherical to ovoidal. Diameter 0.8 to 1.5 μ .	Spherical to ovoidal. Diameter 0.8 to 1.5 μ .
Strain 1E-1354:		
Mycelium.....	Flexuous, continuous, branched. Diameter 0.8 to 1.2 μ .	Flexuous, continuous, branched. Diameter 0.8 to 1.2 μ .
Spores.....	Spherical to ovoidal. Diameter 0.8 to 1.5 μ .	Spherical to ovoidal. Diameter 0.8 to 1.5 μ .
Strain 1E-1355:		
Mycelium.....	Flexuous, continuous, branched. Diameter 0.8 to 1.2 μ .	Flexuous, continuous, branched. Diameter 0.8 to 1.2 μ .
Spores.....	Spherical to ovoidal. Diameter 0.8 to 1.5 μ .	Spherical to ovoidal. Diameter 0.8 to 1.5 μ .
Strain S-604:		
Mycelium.....	Flexuous, continuous, branched. Diameter 0.8 to 1.0 μ .	Flexuous, continuous, branched. Diameter 0.8 to 1.2 μ .
Spores.....	Spheroidal to ovoidal. Diameter 1.5 to 2.0 μ .	Spheroidal to ovoidal. Diameter 1.5 to 2.0 μ .
Strain A-377:		
Mycelium.....	Flexuous, continuous, branched. Diameter 0.7 to 1.0 μ .	Flexuous, continuous, branched. Diameter 0.8 to 1.2 μ .
Spores.....	Spheroidal to ovoidal. Diameter 1.5 to 2.0 μ .	Spheroidal to ovoidal. Diameter 1.5 to 2.0 μ .
Strain 1E-2803:		
Mycelium.....	Flexuous, continuous, branched. Diameter 0.8 to 1.2 μ .	Flexuous, continuous, branched. Diameter 0.8 to 1.2 μ .
Spores.....	Spherical to ovoidal. Diameter 0.8 to 1.5 μ .	Spherical to ovoidal. Diameter 0.8 to 1.5 μ .

NOTE.—Mycelial and spore morphology, as viewed through the light microscope, is apparently similar for strains 1E-1352, 1E-1354, 1E-1355 and 1E-2803 as for strains A-377 and S-604. However, the diameters for typical mycelium and for spores of the former strains appear to be characteristically smaller than for the latter. All strains demonstrate continuous, flexuous, branched mycelium with an occasional tendency of aerial hyphae to develop hooks or loops or to coil into primitive loose spirals as is typical of the species *S. aureofaciens*.

The conditions of the fermentation are generally the same as for the presently known methods of producing chlortetracycline by fermentation. That is, the fermentation medium contains the usual assimilable sources of carbon, nitrogen and inorganic salts. Suitable nutrient substances include starch, dextrose, cane sugar, glucose, molasses, soy bean meal, milk solids, yeast, meat extracts, peptone, urea, cornsteep liquor, cottonseed meal, distillers' solubles, glyceride oils, fish meal and other conventional substances. The inorganic salts include such things as calcium carbonate, ammonium sulfate, ammonium chloride, and salts of the various trace elements such as manganese, cobalt, zinc, copper, iron and the like.

The other general conditions of the fermentation such as hydrogen ion concentration, temperature, time, rate of aeration, preparation of the inoculum, sterilization, inoculation and the like are conventional and may be similar to those for the production of 7-chloro-6-demethyltetracycline shown in U.S. Pat. No. 2,878,289 (McCormick et al.).

The recovery of the 7-chloro-6-demethyltetracycline from the fermentation liquor is conventional and need not be described, as numerous methods for the recovery of this product from fermentation liquors have already been published.

The invention will be described in greater detail in conjunction with the following specific examples.

EXAMPLE 1

A fermentation medium was prepared which contained the following ingredients:

Starch—45 grams
 CaCO_3 —10.5 grams
 NH_4Cl —1.5 grams
 Cottonseed flour—45 grams

Yeast—1.5 grams

Water—q.s. to—1000 milliliters

This medium was dispensed in appropriate amounts into flasks containing 3 percent (vol./vol. of medium) of lard oil and then sterilized. These flasks were then divided into 14 approximately equal groups. Each group was then inoculated with a vegetative inoculum of one of the following strains of *S. aureofaciens*.

S-604 (ATCC 12551)

S-1071 (ATCC 12552)

V-62 (ATCC 12553)

B-740 (ATCC 12554)

V-138

E-475

E-1311

ED-1723

ED-2047

ED-2314

1E-1352 (NRRL 3201)

1E-1354 (NRRL 3202)

1E-1355 (NRRL 3203)

1E-2803 (NRRL 3235)

All of the flasks were then incubated on a rotary shaker with a 2 1/2-inch circulator motion at 185-200 r.p.m. at 25° C. for 25 180 hours. Samples were withdrawn, diluted with 199 parts of water, and the reflectance curves determined as set forth hereinabove. The results are set forth in FIGS. 1 through 14. The harvest mash assays are recorded in table I below. These assays were performed using the following methods:

30 Assay No. 1: This assay is based upon the difference in the rates of conversion of 7-chloro-6-demethyltetracycline and 6-demethyltetracycline to their respective anhydro forms by an acid catalyzed, first order reaction. The degree of conversion to the anhydro form depends upon time, temperature and acid strength involving a reaction which results in a decrease in absorbance at 368 m μ and an increase in absorbance at 440 m μ . Assay No. 2: This assay is based upon the same basic principle as assay no. 1 except that in this case the sample is treated with 40 acid to degrade all tetracyclines present to the anhydro form in one instance and compared to a sample treated with water in the second instance.

Assay No. 3: The assay figures in this column were determined by a conventional paper chromatographic procedure using the 45 system 0.3 M sodium phosphate n-butyl acetate, giving an *R*_f of 0.30 for 6-demethyltetracycline. Three similar systems, published in the Journal of the American Chemical Society, Vol. 79, pp. 4561-4563 (1957), (McCormick et al.) are listed below.

50

	System	6-Demethyltetracycline <i>R</i> _f
55	0.3 M Sodium Phosphate/n-butanol (pH 3.0) Mac Ilvaine's Buffer/ethyl acetate (pH 4.7)	0.30
60	0.3 N H_3PO_4 , 0.1% CCl_4COOH 9:1 CHCl_3 -n-Butanol	0.27
		0.22

65 In this table I, the percent 6-demethyltetracycline (Column 4) of the first four strains (S-604, S-1071, V-62 and B-740) was determined by finding the amount of 6-demethyltetracycline by paper chromatography (column 3) and dividing this figure by the total amount of demethyltetracyclines determined by

70 spectrophotometric analysis (column 1) plus the chromatographic analysis (column 3). The percent 6-demethyltetracycline (column 4) produced by the balance of the strains is determined by dividing the chromatographic analysis (column 3) the spectrophotometric analysis of the total tetracyclines (column 2).

75

TABLE I

S. aureofaciens strain No.	Assay			Percent DMTC
	No. 1 DMCTC, γ/ml.	No. 2 Total tetracyclines, γ/ml.	No. 3 DMTC, γ/ml., quantitative paper chromatogram	
S-604	1,193	2,037	110	8.4
S-1071	876	2,428	138	13.1
V-62	1,177	2,255	573	32.7
B-740	1,042	2,553	380	26.7
V-138	950	1,817	645	35.5
E-475	2,348	3,601	847	23.5
E-1311	3,186	4,263	820	19.2
ED-1723	1,961	3,304	1,320	39.9
ED-2047	4,726	6,316	1,775	28.1
ED-2314	1,946	6,650	1,100	16.5
1E-1352	5,780	5,990	247	4.1
1E-1354	4,420	4,565	145	3.9
1E-1355	6,060	6,390	230	4.2
1E-2803	6,034	6,220	186	2.8

What is claimed is:

1. The process of producing 7-chloro-6-demethyltetracycline which comprises cultivating a strain of *Streptomyces*

aureofaciens which produces 7-chloro-6-demethyltetracycline to the substantial exclusion of other tetracyclines selected from the group consisting of those having accession numbers NRRL 3201, NRRL 3202, NRRL 3203 and NRRL 3235, and

5 mutants thereof under submerged aerobic conditions in an aqueous nutrient medium containing assimilable sources of carbon, nitrogen and inorganic salts until substantial quantities of 7-chloro-6-demethyltetracycline are produced, said 7-chloro-6-demethyltetracycline-producing strain of *Streptomyces aureofaciens* being characterized by its ability to impart to a 200-fold aqueous dilution of the whole harvest mash a color characterized by a reflectance curve, when plotted linearly, wherein the values of the percent reflectance at 460 m μ , 540 m μ , 560 m μ and 660 m μ when substituted into the formula:

$$\delta R = R_{540} + R_{560} - 1.1 R_{460} - 0.9 R_{660} - 2.0$$

give a positive value for δR .

2. A process according to claim 1 in which the amount of 6-demethyltetracycline produced is no more than 5 percent by weight of the amount of 7-chloro-6-demethyltetracycline produced.

UNITED STATES PATENT OFFICE
CERTIFICATE OF CORRECTION

Patent No. 3,616,239 Dated October 26, 1971

Inventor(s) John Andrew Growich, Jr.

It is certified that error appears in the above-identified patent and that said Letters Patent are hereby corrected as shown below:

In the Abstract "value of R is obtained" should be -- value of ΔR is obtained --; "m" should be -- μ --; following "formula:" insert -- $R=R_{540} + R_{560} - 1.1 R_{460} - 0.9 R_{660} - 2.0$ --.

Column 1 Lines 13, 17, 49

Column 3 Lines 5, 6, 8, 10, 41, 45 "s" should be -- Δ --.

Column 3 Line 71 "6 demethyltetracycline" should be -- 6-demethyltetracycline --.

Signed and sealed this 30th day of May 1972.
